COMBINED JACK-O-LANTERN TOY AND CONTAINER

Joseph Green, 54 Prospect Ave, Hewlett,
Long Island, N.Y.

Filed May 4, 1965, Ser. No. 85,099

Term of patent 7 years

(Cl. D34—4)

FIG. 1 is a perspective view of a combined jack-o'-lantern toy and container showing my new design;

FIG. 2 is a side elevational view; and

FIG. 3 is a back elevational view.

I claim:

The ornamental design for a combined jack-o'-lantern toy and container, substantially as shown.
